(Cl. D15—1)

To all whom it may concern:

Be it known that I, Jack Sherman, a citizen of the United States and a resident of the city of Los Angeles, in the county of Los Angeles and State of California, have invented a new, original, and ornamental Design for Chair, of which the following is a specification, reference being had to the accompanying drawing, forming part thereof, in which:

Fig. 1 is a front, perspective view of a chair, showing my new design; and

Fig. 2 is a rear, perspective view.

I claim:

The ornamental design for a chair, as shown.
